Primary Examiner — Rosemary K Tarcza(74) *Attorney, Agent, or Firm* — Greer, Burns & Crain, Ltd.;
Patty Chidiac; Mark W. Croll(57) **CLAIM**

The ornamental design for a battery pack for a combustion tool, as shown and described.

DESCRIPTION

FIG. 1 is a top perspective view of the present battery pack;
 FIG. 2 is a right side view of the battery pack of FIG. 1;
 FIG. 3 is a left side view of same;
 FIG. 4 is a front view of the battery pack of FIG. 1;
 FIG. 5 is a rear view of same;
 FIG. 6 is a top view of same; and,
 FIG. 7 is a bottom view of the battery pack of FIG. 1.
 The broken lines shown in the drawings are included for the purpose of illustrating environmental structure and form no part of the claimed design.
